UNITED STATES PATENT OFFICE.

MORRIS N. DRUCKER, OF CINCINNATI, OHIO.

DESIGN FOR A TRUNK-LOCK.

No. 38,129.

Specification for Design.

Patented July 17, 1906.

Application filed June 9, 1905. Serial No. 264,526. Term of patent 7 years.

To all whom it may concern:

Be it known that I, MORRIS N. DRUCKER, a citizen of the United States of America, and a resident of Cincinnati, county of Hamilton, State of Ohio, have invented a certain new, original, and ornamental Design for a Trunk-Lock, of which the following is a specification.

The drawing is a perspective view of a trunk-lock embodying my invention.

I claim—

The new, original and ornamental design for a trunk-lock as shown.

MORRIS N. DRUCKER.
